UNITED STATES PATENT OFFICE.

THEODOR KAISER, OF WARBLINGEN, GERMANY.

FLY-CATCHER.

1,128,454.

Specification of Letters Patent. Patented Feb. 16, 1915.

Application filed April 28, 1910. Serial No. 557,701.

To all whom it may concern:

Be it known that I, THEODOR KAISER, manufacturer, a subject of the King of Wurttemberg, residing at Warblingen, in the Kingdom of Wurttemberg, Germany, have invented certain new and useful Improvements in Fly-Catchers; and I do hereby declare the following to be a full, clear, and exact description of the invention, such as will enable others skilled in the art to which it appertains to make and use the same.

The present invention consists in a fly catcher in which a tape covered with adhesive is drawn out of a holder serving to contain the adhesive material. This fly catching device is distinguished from other previous constructions in having at the end of the tape a pin which serves to readily attach the device at any desired point, while the tape itself may serve to display advertisements. The pin or stud is preferably fixed to the ceiling because flies, as is well known, prefer to remain in the upper portions of the room and are thus more quickly caught.

In the accompanying drawing the improved fly catcher is illustrated in Figures 1 and 2. Of these—Fig. 1 represents an elevation of a fly-catcher, Fig. 2 is a perspective view of the same.

At the free end of the strip *a* covered with adhesive, there is fixed an attaching device in the form of a little nail or pin *b* which can be easily attached anywhere. The end of the strip *a* is fastened in the well known manner within a box serving to contain the adhesive material. The entire length of the strip can be printed with advertisements on both sides, which can easily be read through the transparent adhesive. The strip *a* and also the receptacle *c* may be made of any suitable material.

By referring to the drawing, it will be noted that the nail or other piercing attaching device *b* is connected to the end of the strip *a* by a flexible connection *d* which, in the present instance, is shown as consisting of a link passing through perforations in the nail head and in the free end of the strip end *a*. This flexible con-

nnection of the piercing device enables the latter, and with it, the fly catcher to be attached to any pierceable surface, whether the same be horizontal, vertical or inclined. 55 This feature makes the article very convenient of use.

The nail or piercing device *b*, as shown, comprises a flat head and a pointed stem. This construction greatly facilitates the insertion of the nail at any point of the room without leaving any disfiguring mark when the nail is withdrawn. The flat head, when the nail is driven home, serves to securely hold the same against lateral movement and, 60 therefore, counteracts any tendency to loosen the hold of the nail. The arrangement of the nail having a flat head and a pointed stem which is attached to the strip *a*, by a flexible connection *d* results also in 70 the advantage that when the strip *a* is coiled up and entirely within the receptacle *c* the flat headed nail may be inserted into the box piercing the same and piercing also a number of the coils of the strip *a*, thereby 75 securing the parts in place and the strip against withdrawal, while at the same time the said nail is entirely out of the way, in view of the fact that the flat head lies snugly against the side of the receptacle. 80 A very convenient article, which takes up a minimum of space and is not readily deranged, is therefore afforded for the market.

What I claim and desire to secure by Letters Patent is:—

A fly-catcher comprising a casing for containing adhesive matter and a strip coiled within said casing, having its end extending beyond said casing, in combination with a nail having a thin flat head and a shank 90 pointed at its extremity, and a flexible connection for uniting the head to the end of the strip, said flexible connection being attached to the flat head of the nail and to the end of the strip.

In testimony whereof I hereunto affix my signature in the presence of two witnesses.

THEODOR KAISER.
